FIG. 1

FIG. 2

FIG. 3

FIG. 4

FIG. 5

FIG. 1 is a front, top and right side perspective view of a television receiver, showing my new design;

FIG. 2 is a front elevational view;

FIG. 3 is a right side, bottom and rear perspective view;

FIG. 4 is a top plan view; and

FIG. 5 is a left side elevational view, the right side being substantially a mirror image thereof.

A portion of the extended telescopic antenna is broken away in FIGS. 2 and 3 for convenience in illustration. Portions of the drawing figures are shaded to indicate contrast in appearance, and portions are diagonally lined to indicate transparency.

I claim:

The ornamental design for a television receiver, as shown and described.
